NONREFILLABLE BOTTLE

Lester M. Bumgarner, Port Townsend, Wash.

Application February 20, 1946, Serial No. 648,878

3 Claims. (Cl. 215—23)

1

This invention relates to improvements in non-refillable bottles, and more particularly to a bottle in which a valved plug assembly may be inserted to permit the contents of the bottle to be poured out, but which renders it impossible to refill the bottle for use again.

An object of the invention is to provide a non-refillable bottle construction which will include means for inserting and locking it in the neck of a bottle, whereby the contents thereof may be dispensed, and refilling of the bottle will be made impossible.

A further object of the invention is to provide an improved non-refillable bottle construction which will be positive in operation, and which will be relatively inexpensive to manufacture and produce.

Other objects will appear as the description proceeds.

In the accompanying drawings which form a part of this application,

Figure 1 is a vertical sectional view of the improved non-refillable bottle, showing the valved plug in position within the neck of the bottle with the bottle cork in position in the base of the bottle neck;

Figure 2 is a vertical sectional view of the improved non-refillable bottle, showing the valved plug pushed down in the bottle neck into locked position and the bottle cork shown in dotted lines after being pushed into the bottle body;

Figure 3 is a partial vertical sectional view showing the neck of the bottle with valve mechanism in pouring position;

Figure 4 is a side elevation of the plug with valve mechanism removed;

Figure 5 is a view taken on the line 5—5 of Figure 4;

Figure 6 is a perspective view of the aluminum tube for receiving the locking plugs;

Figure 7 is a perspective view of one of the locking plugs;

Figure 8 is a side elevation of the top metal valve cut-off cap;

Figure 9 is a side elevation of the apertured cut-off valve body;

Figure 10 is a bottom plan view of the valve body shown in Figure 9;

Figure 11 is a side elevation of the bottom metal valve cut-off cap;

Figure 12 is a top plan view of the bottom valve cut-off cap;

Figure 13 is a side elevation of the bottle cork showing the seat in its upper surface shown in dotted lines;

2

Figure 14 is a plan view of the bottle cork shown in Figure 13;

Figure 15 is a vertical sectional view through the bottle neck without the non-refillable valve mechanism, and

Figure 16 is a view taken on the line 16—16 of Figure 15.

Like characters of reference are used throughout the following specification and the accompanying drawings to designate corresponding parts.

In carrying out the instant invention, there is provided a glass bottle having a body 1, and an elongated neck 2, formed with an annular flange 3 adjacent its upper end, and a threaded portion 4 at the top of the bottle neck 2. A series of openings 5 are formed through the bottle neck 2 from the flange 3 to the bottle body, at equidistant spaced points about the neck. Preferably three openings or passages 5 will be utilized. A cork washer 6 will be adapted to fit or seat on the flange 3, and a thin metal cap closure 7 will be threaded on the upper end of the bottle neck to seat on the washer to seal the bottle.

A pair of vertically extending tapering grooves or slots 8 will be formed in the opposite sides of the inner surface of the bottle neck 2, said grooves or slots being of increasing depth from their upper ends to their lower ends.

A glass valve supporting plug 9 will be inserted within the neck 2 of the bottle 1 and will be formed with a rounded upper end 10. A pair of oppositely disposed off-set grooves 11 and 12 will be formed in the outer surface of the plug 9, as clearly shown in Figure 5 of the drawings, and will terminate in the apertures 13 and 14 extending through the plug to connect with the valve receiving recess 15 formed in the bottom of the plug 9. An annular groove 16 is formed about the lower end of the plug 9 and is adapted to receive the cork washer 17, to seal the space between the adjacent surfaces of the plug and the bottle neck 2. A transverse opening 18 is formed through the plug 9 and is adapted to receive the aluminum locking tube 19 which extends flush with the sides of said plug 9. The metal locking pins or plugs 20 and 21 are positioned within the body or tube 19 and a coil spring 22 is placed in the tube 19 between the plugs 20 and 21 to force the same outwardly to be engaged in the oppositely disposed vertically extending tapered grooves or slots 8 in the bottle neck 2.

A cork washer 23 is positioned within the valve receiving recess 15 at the upper or inner end thereof, and a second cork washer 24 is posi-

tioned within the lower end of the recess 15 and supports the cylindrical valve body 25, said body being formed with a central aperture 26 and a series of circumferentially arranged apertures 27, extending through its length. The top metal valve cut-off cap 28 is of the same diameter as the valve body 25, and supports the depending rubber guide rod 29, which is extended through the rubber disk washer 30 which is slightly larger in diameter than the top cut-off cap 28 and the valve body 25. The rod 29 is also extended through the central aperture 26 in the valve body 25, and is secured to the bottom metal valve cut-off cap 31, which is positioned below the valve body 25, and is formed with the crossed slots 33 in its upper surface. A cork plug 34 formed with a central circular recess 35 in its upper surface will be in the bottom of the bottle neck 2 until the plug 8 is forced down to displace the cork 34 driving the same into the bottle 1.

From the foregoing description, the operation of the non-refillable bottle will be apparent, but will be described as follows: When the bottle is full of a beverage, the plug will be in raised position as shown in Figure 1 of the drawings and the cork plug 34 will be positioned in the bottom of the neck 2. The plug 9 will be forced downwardly as shown in Figure 2 of the drawings, thereby forcing the cork 34 down into the bottle 1. The valve body 25 and its associated parts will now be operable to permit the beverage to be poured from the bottle when in position shown in Figure 3 of the drawings. When the bottle is placed upright, the top cap 28 will seal the apertures 26 through the valve body 25 so that the bottle may not be refilled. The locking plugs 21 in the tube 19 will lock the plug 9 in the grooves 8 in the bottle neck so that the plug 9 may not be removed.

While the preferred embodiment of the invention has been illustrated and described, it will be understood it is not intended to limit the scope of the invention thereto, as many minor changes in detail of construction may be resorted to without departure from the spirit of the invention.

Having thus described my invention, what I claim as new and desire to secure by Letters Patent of the United States is:

1. In a non-refillable bottle having a neck, said neck having longitudinally extending opposed tapered slots formed in the inner surface of the wall of said neck, a valve supporting plug slidably disposed in said bottle neck, spring projected locking pins disposed transversely of said plug adapted to seat in the opposed tapered slots in

the bottle neck for locking said plug in said bottle neck, said plug being formed with a valve chamber in its inner end, oppositely disposed longitudinally extending offset slots formed in the outer surface of said plug communicating at their inner ends with the inner end of said valve chamber, a longitudinally ported valve body in said valve chamber, a valve stem disposed longitudinally and centrally through said valve body, and valve closure caps on the ends of said valve stem being alternately engageable with the ends of said valve body as said body is tilted to pouring position and then is placed in its normal upright position.

2. In a non-refillable bottle having a neck, said neck having longitudinally extending opposed tapered slots formed in the inner surface of the wall of said neck, a valve supporting plug slidably disposed in said bottle neck, spring projected locking pins disposed transversely through said plug adapted to seat in the opposed tapered slots in the bottle neck for locking said plug in said bottle neck for limited longitudinal movement, said plug being formed with a valve chamber in its inner end, oppositely disposed longitudinally extending offset slots formed in the outer surface of said plug communicating at their inner ends with the inner end of said valve chamber, a longitudinally ported valve body in said valve chamber, a valve stem disposed longitudinally and centrally through said valve body, valve closure caps on the ends of said valve stem being alternately engageable with the ends of said valve body as said bottle is tilted to pouring position and then is placed in its normal upright position, and packing washers about said valve body and said valve stem and between said plug and said bottle neck.

3. The subject matter as claimed in claim 1, and a sealing cork disposed in the neck of said bottle below said plug adapted to be pushed inwardly from said neck and into said bottle by the inward movement of said plug from its uppermost to its lowermost position.

45 LESTER M. BUMGARNER.
